REFRACTORY BURNER THROAT

Arleigh W. Anderson, Huntington Park, Calif.,
assignor to Peabody Engineering Corporation,
New York, N. Y., a corporation of New York

Application November 16, 1938, Serial No. 240,609

8 Claims. (Cl. 110—1).

This invention relates to refractory burner throats for furnaces and has for an object to provide a burner throat having novel and improved details of construction and combinations of parts.

Another object is to provide a burner throat formed by refractory blocks so constructed and arranged that the replacement of the individual blocks is facilitated.

Another object is to provide a sectional refractory block having a nose section which may be removed and replaced without replacing the entire block.

Another object is to provide novel and improved means for securing the nose section in the furnace wall.

Another object is to provide means for securing the nose section without the use of extra bolts or stays.

Another object is to provide a block for a burner throat having a nose section loosely held so as to permit expansion or distortion thereof due to the heat of the flame.

Another object is to provide novel and improved means for securing the blocks in the furnace wall.

Various other objects and advantages will be apparent as the nature of the invention is more fully disclosed.

Although the novel features which are believed to be characteristic of this invention will be more particularly pointed out in the claims appended hereto, the invention itself will be better understood by referring to the following description, taken in connection with the accompanying drawing forming a part thereof, in which a specific embodiment of the invention has been set forth for purposes of illustration.

In the drawing:

Fig. 1 is a side elevation, partly in section, of a burner assembly embodying the present invention;

Fig. 2 is a front elevation thereof taken from within the combustion chamber; and

Fig. 3 is a detail view of the securing bolt for the blocks.

In the following description and in the claims certain specific terms are used for convenience in referring to various details of the invention. These terms, however, are to be given as broad an interpretation as the state of the art will permit.

Referring more particularly to the drawing, the invention is shown as applied to a furnace wall 10 forming a part of the combustion chamber of a furnace of any well known and standard construction. The wall 10 is provided with

a circular opening 11 in which the burner throat blocks are positioned. The burner throat is formed by a ring of sectional refractory blocks 12, each block comprising a base section 12a and a nose section 12b having cooperating dovetailed shoulders 14 and 15 respectively which serve to hold the nose sections 12b in position. The blocks 12 are each provided with a curved inner surface 16 which is suitably shaped to form the usual flared burner throat. In the embodiment shown, the nose section 12b is provided with a surface 17 extending from the shoulder 15 radially to the outer edge of the block and with an inclined surface 18 extending from the shoulder 14 to the inner curved surface 16 of the block. The base section 12a is provided with complementary surfaces which engage the surfaces 17 and 18 for securing and supporting the nose section. The inclined surface 18 provides a wedge shaped support which wedges the nose section against the inner peripheral surface of the wall 10 at the opening 11. The transverse surface 17 positions the block axially. The peripheral surface of the nose section is curved as at 19 about the point 20 as a center to permit the nose section to pivot about said point, as shown in dotted lines in Fig. 1, for removal from the assembly without disturbing the base section. The inner peripheral surface of the wall 10 at the opening 11, engaging the outer peripheral surface of the nose sections 12b, serves to securely hold the same while the burner is being operated.

For securing the blocks in position and supporting the air register, to be described, there may be provided a plate 21, having an opening 22 registering with the burner throat. The plate 21 may be secured by any suitable means such as the boiler columns (not shown). A sheet 21a of insulating material may be disposed beneath the plate 21 if desired.

The base sections 12a may be provided with recesses 23 forming a continuous annular recess around the entire ring of blocks. A set of hex-bolts 24 having heads 25 extend through the plate 21 and are secured thereto as by nuts 26 with the heads 25 in the recesses 23. The bolts 24 may be spaced around the opening 11 so that the heads 25 form a substantially continuous supporting ring for the refractory blocks 12. The plate 21 may overlap the opening 11 to form a flange 27 which serves as a stop and positioning means for the blocks 12. The peripheral surface 28 of the base sections 12a is spaced from the inner surface of the wall 10 at the opening 11.

to provide an annular channel in which the bolts 24 may be positioned.

An air register 30 may be secured to the plate 21, as by means of an annular support 31 forming a part of the air register and having a flange 32 secured to the plate 21 by bolts 33. The air register may be of any standard construction and may comprise, in general, a plurality of peripheral doors 34 which are provided with suitable 10 actuating mechanism and are supported between the annular member 31 and a front plate 35. The front plate 35 may be secured in a rectangular frame 36 attached to a wall 37 forming, with the wall 10, an air space through which air is supplied to the air register 30. It is to be understood that when used with natural draft the wall 37 may be omitted and when used with forced draft the air register may be supported by the wall 37 in which case the bolts 33 may be omitted. 15 20 A burner barrel 40 of standard construction, provided with an atomizer tip 41 and a diffuser 42, may be carried by the front plate 35 in a position to extend axially of the burner throat for supplying fuel in the form of a cone-shaped spray which 25 combines with the air from the register 30 for combustion purposes. Any standard type of air register and burner may be employed, such, for example, as that described more in detail in the Peabody Patent 1,628,424. The air register may 30 be adapted to produce a rotating mass of air which is fed inwardly through the burner throat and is diffused by the diffuser 42 so as to effect complete combustion. The burner may, of course, be adapted for use with various types of 35 fuel, such as, for example, solid, liquid or gaseous fuel and is adapted to produce a cone-shaped flame which extends inwardly within the combustion chamber of the furnace.

The nose sections 12b of the throat blocks are 40 subjected to the intense heat of the flame. Hence this portion of the blocks deteriorates most rapidly. Furthermore, it is subjected to extreme temperature changes which cause contraction and expansion thereof and frequently result in 45 the cracking of the blocks. The present invention permits the nose sections to be made of a higher grade refractory than the base sections if desired and also permits the nose sections to be replaced without requiring replacement of the 50 entire block.

The throat is assembled in the usual manner, the blocks 12 being secured by the bolts 24 and the recesses being filled with plastic refractory if desired. Inasmuch as the nose sections 12b 55 are securely held by the cooperating surfaces of the bases 12a and the inner surface of the opening 11 in the wall 10, no additional fastening means for the nose sections is required. They may be readily removed in the manner above 60 described without removing or loosening the base sections.

It is to be understood that the nose sections 65 may be held by plastic refractory if desired. In removing the nose sections it may be necessary to break away one of the sections to release the others which are held by the keystone effect thereof. The last section may be inserted by removing the shoulder 15 thereof and sliding the section in axially from the inside of the furnace, 70 using plastic refractory if desired to secure the same.

The surfaces 17 and 18 are preferably provided with sufficient clearance so that a limited amount of movement is permitted for the nose sections 75 12b. This permits the nose sections to freely

expand and contract in response to temperature changes and to automatically position themselves so as to equalize the stresses produced therein. In this way the life of the blocks is materially increased.

It is to be understood that the shape of the flared surface 16 of the blocks 12 may be varied in accordance with the particular type of burner and with the particular fuel being employed so as to produce a flame having the desired characteristics. Any desired type of supporting means may be employed for securing the base sections, the bolts 24 having been shown only for purposes of illustration. It is to be understood that the bolts 24 may be omitted if desired 15 and the blocks secured by the plastic refractory or by the close fit of the various blocks in the ring. In certain instances means may be provided for admitting air to the space around the blocks. This air passes through the openings 20 around and between the blocks and between the base and nose sections and thereby cools the blocks and increases the life thereof.

Although a specific embodiment of the invention has been shown, it is to be understood that the invention is capable of various uses and that various changes and modifications may be made therein as will readily appear to a person skilled in the art. The invention is only to be limited in accordance with the following claims when 30 interpreted in view of the prior art.

What is claimed is:

1. In a furnace having a wall provided with an opening, a ring of sectional blocks in said opening forming a burner throat, each of said blocks comprising separate base and nose sections, means securing said base sections to said wall, said base and nose sections having shoulders formed thereon in dovetailed relationship to hold the nose sections in position against the 40 inner peripheral surface of the wall at said opening, said shoulders being arranged to release the nose sections when the nose sections are tilted inwardly.

2. In a furnace having a wall provided with 45 an opening, a ring of sectional blocks in said opening forming a burner throat, each of said blocks comprising separate base and nose sections, means securing said base sections to said wall, said base and nose sections having interlocked shoulders and having complementary surfaces extending from said shoulders to the inner peripheral surfaces of the blocks, said complementary surfaces being inclined to wedge the nose sections against the inner peripheral surface of said wall at said opening.

3. In a furnace having a wall provided with an opening, a ring of sectional blocks in said opening forming a burner throat, each of said blocks comprising separate base and nose sections, means securing said base sections to said wall, said base and nose sections having interlocked shoulders and having complementary surfaces extending from said shoulders to the inner and outer peripheral surfaces respectively of the 65 blocks, the first complementary surfaces being inclined to wedge the nose section against the inner peripheral surface of the wall at said opening, and the second complementary surfaces being normal to the axis of the throat to position the nose section.

4. A refractory burner throat formed by a ring of sectional blocks each having a base section adapted to form the outer part of said throat and a separable nose section forming 75

the inner part of said throat, said base and nose sections having interlocked shoulders holding the nose sections in position, said nose sections having a curved rear peripheral surface to permit removal thereof by tilting their forward ends inwardly toward the axis of the burner throat.

5. In a furnace having a wall provided with an opening, a ring of refractory blocks in said opening forming a burner throat, said blocks having an outer annular groove extending around said ring and having longitudinal channels extending from the front of said blocks into communication with said groove and securing means for said blocks comprising bolts in said channels and having heads extending into said groove.

6. In a furnace having a wall provided with an opening, a ring of refractory blocks in said opening forming a burner throat, said blocks having an outer annular groove extending around said ring and a peripheral surface spaced from said wall to provide an annular channel communicating with said groove, and securing means for said blocks comprising bolts in said

channel and having heads extending into said groove.

7. In a furnace having a wall provided with an opening, a ring of sectional blocks in said opening forming a burner throat, each of said blocks comprising separate base and nose sections, means securing said base sections in said wall opening, said base and nose sections having interlocking surfaces removably securing said nose sections to said base sections and holding the same in position against the inner periphery of said wall opening whereby said securing means serves to secure both the base and nose sections in said wall and whereby said nose sections may be removed without releasing said securing means.

8. The invention set forth in claim 7 in which said nose sections are each provided with an arcuate rear peripheral surface cooperating with said interlocking surfaces to permit removal of the nose sections without disturbing said base sections by tilting the forward ends thereof inwardly toward the axis of the burner throat.
